(57) CLAIM

The ornamental design for a display panel or portion thereof with a transitional graphical user interface, as shown and described.

DESCRIPTION

FIG. 1 is a front view of a display panel or portion thereof with a transitional graphical user interface showing a first image in a sequence of our design;

FIG. 2 is a front view of a display panel or portion thereof with a transitional graphical user interface showing a second image in the sequence thereof;

FIG. 3 is a front view of a display panel or portion thereof with a transitional graphical user interface showing a third image in the sequence thereof;

4 is a front view of a display panel or portion thereof with a transitional graphical user interface showing a fourth image in the sequence thereof;

FIG. 5 is a front view of a display panel or portion thereof with a transitional graphical user interface showing a fifth image in the sequence thereof;

FIG. 6 is a front view of a display panel or portion thereof with a transitional graphical user interface showing a sixth image in the sequence thereof;

FIG. 7 is a front view of a display panel or portion thereof with a transitional graphical user interface showing a seventh image in the sequence thereof;

FIG. 8 is a front view of a display panel or portion thereof with a transitional graphical user interface showing an eighth image in the sequence thereof;

FIG. 9 is a front view of a display panel or portion thereof with a transitional graphical user interface showing a ninth image in the sequence thereof;

FIG. 10 is a front view of a display panel or portion thereof with a transitional graphical user interface showing a tenth image in the sequence thereof; and,

FIG. 11 is a front view of a display panel or portion thereof with a transitional graphical user interface showing an eleventh image in the sequence thereof.

The appearance of the image sequentially transitions between the images shown in FIGS. 1 through 11. The process or period in which one image transitions into another forms no part of the claimed design.

The outermost broken line illustrates the article and forms no part of the claimed design. The broken line rectangle illustrates a display panel or portion thereof and forms no part of the claimed design. The remaining broken lines illustrate portions of the graphical user interface and form no part of the claimed design.
